SPOOL HOLDER

William C. Adlman, New York, N. Y.

Application November 15, 1947, Serial No. 786,305

1 Claim. (Cl. 87—22)

1
This invention relates to spool holders for braiding machines, of the type in which a weight is used to tension the thread while the thread is unwinding from the spool.

The invention provides a spool holder for braid-
ers in which the thread is elastically suspended after it leaves the spool, by the use of a long heli-
cal spring which is stretched by the tension of
the thread and seeks to return to its initial position, the spring in its operative position being
stretched about two times its initial unstretched condition. The spring is connected directly with
the thread and has no weights of any kind, the
free floating upper end of the spring being entirely
free to float in in response to the thread, and
the free upper end of the spring abutting directly
against the pawl or detent which engages the
ratchet on the upper end of the spool or bobbin,
and which pawl releases the bobbin to furnish an
additional supply of thread as known, a weighted
loop member, however, being provided outside
of the spool, through which the thread passes
as it leaves the spool or bobbin and before it
passes through the spring.

By the use of the delicate free floating of the
thread as it passes through the spring end, the
thread is not broken, and the speed of the ma-
chine may be increased considerably over those
machines in which a weight in the bore of the
bobbin is used.

The tensions of the springs are selected in re-
lation to the thread strength.

The invention will be further described, an em-
bodiment shown in the drawings, and the invention
will be finally pointed out in the claims.

In the accompanying drawings,

Fig. 1 is a side view of a spool holder for braid-
ing machines of the known type, with the im-
provement embodied therein, partly in section;

Fig. 2 is a detail sectional view on line 2—2 of
Fig. 1.

Fig. 3 is a sectional view of the cap;

Fig. 4 is a perspective view of the improved cap
for the spring; and

Fig. 5 is a partial diagrammatical view of the
spool holder with the improved spring in its ini-
tial position.

Similar characters of reference indicate corre-
sponding parts throughout the various views.

Referring to the drawings, the structure there-
in shown, with the exception of the location and
working of the spring, and the weighted loop
member are known. Structures of this kind have
been in use with a weight in the bore of the bob-
bin, instead of the spring, but such structures

when used with a weight have the disadvantage
that the thread was subjected to uneven pulls
and release, which caused the tearing of the
threads. It is believed that this alternate pull
and release is due to the non-responsive inertia
of the weight.

The improvement consists in providing a long
helically coiled spring, anchored at its lower end
and freely movable at its upper end, disposed
10 within the hollow shaft of the bobbin. The spring
is provided at its upper end with an eyelet for
the thread, the length of the spring along its axis
being about 3 inches from end convolution to end
convolution and about 6 inches when in operat-
15 ing expanded position. When stretched to the 6
inches, the upper eyelet of the spring is in a
position to abut against the pawl or detent to
release it, to permit the bobbin to rotate.

The known upright casing 10 has an extension
20 11 provided with an eyelet 12 above the eyelet
13 of the upper end of the spring 15. The lower
end 16 of the spring 15 is permanently secured
to the casing 10 by a pin 17 suitably upset at its
ends as shown by 18 in Fig. 2. Preferably, the
25 end convolutions 19 of the spring 15 are bent in
respect to the longitudinal axis of the spring 15
as shown in Fig. 2, and the pin 17 is passed
through these bent convolutions, whereby a me-
chanical connection between the lower end 16
30 of the spring 15 and the pin 17 is provided. Such
a looped connection allows for a play between
the lower end of the spring and the pin.

The end convolutions 19 of the upper end of
the spring 15 are bent at right angles and also
disposed in line with the longitudinal axis of
the spring 10, and the thread is passed through
the opening of these bent convolutions. To pro-
vide a smooth passage for the thread which will
not wear, there is provided a light plastic cover-
ing 23 for these convolutions. Preferably, also a
covering 24 for the upper end of the spring 15
is provided to prevent the operator's needle, when
threading the thread through the bent up convolu-
tions, from entering into the bore of the spring
15 and become entangled with the convolutions
of the spring 15. Preferably, the eyelet covering
20 and barrier 21 are combined in one piece and
provided with a skirt 22, as shown in Fig. 4. The
barrier 21 is provided with a slot 23 for the seat-
ing of part of the bent up convolutions. The
thread 25 passes through the eyelet 29a of the
plastic covering 20, as shown in Fig. 2.

The other structural portions shown in the
drawings are well known to the art excepting
the following, and require no special description,

excepting that the braider 30 has a vertical shaft 31 on which it rotates, and has an upright thread guider 32, with eyelets 33 and 34.

The spool or bobbin 35 shown in dotted lines seats on the spool support 36 which rests on the plate 37, and the spool 35 has ratchet teeth 35a at its upper end engageable by a pivoted pawl 38 pivoted at 37, and having an eyelet 39. The thread passes from its windings on the spool through the opening 33, then through the movable and somewhat weighted loop 40 and then upwardly through the eyelet opening 34, then downwardly through the eyelet 39, into the bore of the spool and through the end convolution of the spring 15 and then vertically upwards as through the eyelets 39 and 12. From there, as known, it passes vertically upwardly in a radial and inclined position to the apparatus for assembling all of the threads to a braid.

In this general type of spool supporting mechanism, it was found that the thread from the point of the eyelet 13 to the braiding apparatus, would wobble, clearly visible, due to intermittent releases with alternate pulls, and this wobbling had two distinct disadvantages, the breaking of the threads, and requirement to maintain a relatively low speed of operation.

The importance in the use of a long helical spring anchored at its lower end and having its upper end entirely free and unweighted, and of suitable length and tension, is that the pull of the threads on the loose or free end of the spring first causes the upper end convolutions to separate and then as the tension of the convolutions exert their forces on the next adjacent convolutions progressively through the length of the spring, which transfer of forces takes some time, with the full forces of the pull at the free end of the spring transposing itself to the anchored end of the spring only after a time interval, the upper end of the spring is very responsive to any pull or release. In the embodiment, the pull expands the spring and the inherent resiliency then tends to bring the spring back to its position it was in before any pull was exerted. This is in contrast to certain springs of the prior art, which are first compressed and then their inherent resiliency expands them. The improved spring 15 and its use has the important advantage of providing a floating support for the thread, varying in vertical location depending on the action of the braiding apparatus, the speed of rotation of the spool and the speed of rotation of the revolving table supporting the spools.

This elasticity of action on the thread gives the threads an even draw and at the same time permits the machine to be operated at much higher speeds, thus increasing the braid production.

The unweighted and unimpeded floating action of the upper end of the spring satisfies the objective set to assure the free flowing movement of the thread while the braiding action is being carried out, and after many researches and trials, I found this in the principle of a helical spring of considerable length in relation to the diameter of the convolutions and in the diameter of the wire finally utilized, and in the placing of the spring within the bore of the bobbin shaft, and to act directly on the pawl without any levers, enclosures, etc.

In Figure 1 is shown a pawl 38 pivoted at 38a to the upright member 32. The pawl 38 has an eyelet opening 39 for the passage of the thread 25. The pawl 38 is shown in full lines in Fig. 1,

and in this position it locks with the ratchet on the top of the spool or bobbin 35. When the tension of the thread 25 is such as to pull the top of the spring 13 against the pawl 38 at its eyelet 39, the pawl is raised into a position corresponding to the dotted line position shown in Figure 1, and the spool is released to permit the unwinding of the thread. As occasion requires, the pawl is raised from its full line to its dotted line position with the end routine of the spring vertically ascending close to the pawl when in a position corresponding to the dotted line position of the pawl. During the operation of the machine there is a continual alternation of the position of the top of the spring 13 from its position shown in Figure 1, with the pawl interlocking as shown by the full line position of the pawl to a position above the full line position of the spring in Fig. 1 to a position corresponding to about the dotted line position of the eyelet 39 of the pawl 38.

In Fig. 1, the pawl is only shown in the position where it interlocks with the ratchet of the spool, the ratchet and spool not being shown in Fig. 5. The spring as shown in Fig. 5, is in its normal untensioned position. The spring as shown in Fig. 1, is shown in its tensioned position, wherein its length is about twice the length of the spring shown in Fig. 5, the length of the spring being measured from its end convolutions, which are substantially at right angles to the axis of the spring. It will be noted that the diameter of the spring 15 is substantially equal to the diameter of the shaft 10 of the spool holder so that the upper end of the spring or the enclosing member 13 is co-centrally related to the walls of the shaft 10, in order that the free upper end of the spring acts at all times in a straight vertical direction as it is being tensioned by the thread 25. While the cap 13 has been shown as a preferred form, the thread 25 may be passed through the bent up convolutions 19a, as shown in Fig. 2, assuming the cap 13 to be omitted. The important feature is to have a free movement of the thread 25 through the end of the spring so that the upper end of the spring, when tensioned, has a perfect freedom of movement, and thus gives a very quick response to any variation in the tension of the thread 25, as its upper end (not shown) is being braided.

As an example, the length of a coil is $3\frac{1}{4}$ inches, with a convolution diameter of $\frac{3}{8}$ inch and a wire diameter of .020, the wire being of "music wire."

As another example, the length of a coil is 3 inches, with a convolution diameter of $\frac{3}{8}$ inch and a wire diameter of .020 inch, the wire being of "music wire."

With the general pull of the braider the spring is stretched about as shown diagrammatically in Fig. 1, from its normal unstretched position shown in Fig. 5.

I wish it to be understood that I do not desire to be limited to the exact details of construction shown and described, for obvious modifications will occur to a person skilled in the art.

I claim:

In a spool holder for braiding machines having a braiding apparatus, said spool holder having a hollow spool spindle, the combination of a helical spring in said hollow spool spindle having one end secured to the lower end of the spool spindle, and having its upper end free to move and when the spring is stretched to have its upper end in proximity to the upper end of the spool holder, said stretching being to a length about two times the length of the initial length of the spring, the

thread passing through the upper end of the spring and resiliently held thereby when passing from the spool to the braiding apparatus, a vertical thread guiding member to guide the thread from the spool to the spring, having an upper thread guide above the spool and above the extended end of the spring, and having a thread guide about centrally the height of the spool, and a pawl having an eyelet and pivoted to the guiding member, said eyelet being immediately above the upper end of the spring for guiding the thread from the guiding member to the spring and from the spring to the braiding apparatus, said guiding member being parallel with the axis of the spool, with a movable weighted loop disposed between the outgoing side of the central thread guide and the incoming side of the upper thread guide of the guiding member, to loop the

thread as it passes from its spool and before it engages the spring.
